UNITED STATES PATENT OFFICE.

ISAAC D. SMEAD, OF CINCINNATI, OHIO.

HOUSE-HEATING APPARATUS.

SPECIFICATION forming part of Letters Patent No. 700,382, dated May 20, 1902.

Application filed December 16, 1901. Serial No. 86,115. (No model.)

To all whom it may concern:

Be it known that I, ISAAC D. SMEAD, a citizen of the United States, residing at Cincinnati, in the county of Hamilton and State of Ohio, have invented certain new and useful Improvements in House-Heating Apparatus, of which the following is a specification.

My present invention relates to apparatus for heating buildings; and the invention consists, primarily, in a novel construction of a boiler for steam or hot water, and, secondarily, in a covering for the same, whereby it is adapted to heat air for the warming and ventilation of the building, and in a novel construction of the furnace for heating the boiler, together with certain details, all as hereinafter more fully described.

Figure 1 is a front elevation of a portable heating apparatus constructed on my plan. Fig. 2 is a transverse vertical section of the same. Fig. 3 is a similar view of the same, showing the dome or covering constructed to operate as an additional water-heater. Fig. 4 is a similar view showing the dome or covering adapted to heat air. Fig. 5 is a similar view of the apparatus as constructed for heating by steam and having a brick support and covering. Fig. 6 is a transverse horizontal view on the line $x-x$ of Fig. 2. Fig. 7 is a perspective view of a tube-reducing cap, and Fig. 8 shows the manner of applying the same to the boiler-tubes.

The object of this invention is to produce a heating apparatus that shall be adapted to heat all ordinary buildings, but more especially dwellings, with either steam or hot water or with either of these in combination with hot air, as may be desired.

A further object is to so construct the furnace which supports and heats the boiler as to produce perfect combustion, and thereby more fully utilize the fuel and at the same time prevent the formation of smoke.

In order to accomplish these results, I first construct the boiler A of two sheets of steel a and b , pressed into a dome-like or hemispherical shape by means of presses constructed for the purpose, and then unite the two sheets by rivets around their lower edges, as shown in Figs. 2, 3, 4, and 5. Before uniting these sheets I make a series of holes for the insertion of tubes c , these being arranged in

two rows or circles extending entirely around the boiler, near its lower edge, as shown in the several figures. When designed to use water, the lower edge of one or both sheets composing the boiler will be bent so as to fit snugly to the other, as represented in Figs. 2, 3, and 4, so they can be readily fastened together by rivets; but when designed for steam, in which case it is necessary that the boiler shall contain much more water, I make it as shown in Fig. 5, in which it will be seen that the space between the shells or plates a and b is much wider and in which case the lower edges of the sheets are united by the insertion of a circular sheet or strip v , flanged and riveted in the usual manner. In this case also the boiler is provided with a steam-dome L, as shown in Fig. 5. In both cases the tubes c are inserted in the same manner, these tubes serving to largely increase the heating-surface and as the only means for the escape or passage of the products of combustion from within the dome-shaped boiler into the space between the boiler and its dome-shaped covering B and from which space they pass off by a smoke-pipe K, which connects with the space by a suitable opening in the cover located at any desired point.

When used for steam, the boiler-covering B will be composed either of a single sheet of metal on which is placed one or more layers of brick, as represented in Fig. 5, or it may be composed of two such sheets, having the space between them filled with any non-conducting material—such as mineral wool, asbestos, plaster-of-paris, or cement, as represented in Fig. 2, this latter style of covering being equally well adapted for use with either steam or hot water. It is obvious that this dome-shaped cover may also be used as an additional water-heater by simply making it water-tight and providing it with an outflow-pipe f and a return or inflow pipe g , as represented in Fig. 3, these pipes either being connected with the general circulation from the boiler or to separate radiators set in rooms where a less degree of heat is needed or desired. So, too, it is obvious that it may be used for heating air instead of water by simply providing it with suitable inlets and outlets for the air, as represented in Fig. 4, the air thus warmed being conducted where

wanted the same as when a hot-air furnace is used, and in this way a suitable supply of fresh air for ventilation can be supplied to the building when heated either by steam or 5 hot water—a very important provision for the health of the occupants, especially where the heating is effected by what is known as "direct radiation." In all cases this covering however constructed or used will be provided 10 with a series of manholes or openings having removable plates or doors M, as shown in Figs. 1, 2, and 3, by which access can be had to the space within in order to brush off occasionally the fine ash or soot which may acc- 15 cumulate upon the exterior of the boiler or in the tubes and which if permitted to remain lessens the heating capacity of the boiler or apparatus. These openings also serve to enable one to adjust in the tubes, as 20 may be found necessary by the varying drafts of different chimneys and localities, the reducing-caps hereinafter described.

Where the draft of the chimney is excessive, as is sometimes the case, it is desirable 25 to reduce the area of the tubes in order to prevent the heat from passing off too rapidly, and to accomplish this I make a reducing-cap n, as shown in Fig. 7. This consists of a metal disk n, having a hole p at its center 30 and provided with three legs or spurs o, projecting at right angles from one of its faces, as shown in Fig. 7, these projections being so located that when inserted within the tube, as shown in Fig. 8, they will hold the disk se- 35 curely in place, and thereby reduce the size of the opening and decrease the outflow of the hot gases from within the boiler. It is obvious that these caps can be adjusted by drawing them out a little, so as to permit the 40 gases to escape laterally between the end of the tube and the disk, as well as through the small central opening, thereby increasing the area, or when thus drawn out the area can be decreased by shoving them in to the position 45 shown in Fig. 8, the legs or spurs o holding them in position as adjusted. By these means the boiler can be readily adapted to all the varying conditions of draft. These when used are placed in the upper row of tubes.

50 Where the apparatus is to be used in the larger buildings, I make the boiler of an oval instead of a circular form, thereby increasing its size by extending it lengthwise, and thus increase its capacity to any desired extent, 55 its construction being the same in all respects except as to this modification of shape transversely.

The boilers and all their adjuncts of both styles will be made of several different sizes, 60 so as to adapt them to all the varying needs of the public.

It will readily be seen that by making the boiler in the form shown and arranging the outlets for the products of combustion around 65 its lower edge the heat arising from the fire-pot will first strike against the concave surface of the boiler above, where it will be held

as in a pocket until drawn down with uniformity all around at the sides and out through the tubes below, and thence pass over the 70 outside wall of the boiler to the smoke-pipe. By this construction of the boiler with its large number of small tubes I secure a heating-surface far in excess of that in ordinary boilers using the same-sized grate and secure 75 also the application of the heat by direct rays from the fire—two very important results, and which, as experiments show, render this the most effective and economical house-heating apparatus yet produced. 80

In Figs. 1, 2, 3, 4, and 5 I have shown the best methods known to me for setting and utilizing the boiler. The smallest sizes, usually termed "portable boilers," will be provided with a cast-iron support or base 85 made in two sections E and F, as shown in Figs. 1, 2, 3, and 4, in the upper one of which is constructed the fire-pot, composed of unusually thick fire-brick G and H, arranged, as shown, with passages for the admission of 90 air, which becomes heated by contact with the highly-heated fire-brick and is then delivered in horizontal jets above the fuel, where it unites with the gases arising from the fire, thus producing perfect combustion 95 with intense heat, and thereby preventing the formation of smoke. These portable boilers are provided with a dome-shaped covering B, composed of two sheets of metal d and e, united at their base, and, as shown in Fig. 2, 100 the space between them may be filled with any suitable non-conducting material to prevent the escape of heat from the exterior of the boiler, the products of combustion passing between the boiler and the covering to an 105 outlet, which may be located at any suitable point, as indicated in Figs. 2 and 3, or, if preferred, the space within the covering-dome B may be utilized as an additional water-heater, as shown in Fig. 3, or as an air-heater, as 110 shown in Fig. 4, in which cases it will of course be made air and water tight and be provided with suitable inlets and outlets. The oval or larger-sized boilers will preferably be set on brick, as shown in Fig. 5, in 115 which case the covering may be constructed as above described or it may be composed of brick resting on a metallic support corresponding in shape with that of the boiler, as represented in Fig. 5. In all cases this covering will be provided with openings M, (shown in the several figures,) having doors or removable plates to afford access to the space between the boiler and its covering in order 120 to insert or remove the tube-reducers when necessary and also to brush off the fine ash or soot which may accumulate on the outer surface of the boiler.

I am aware that a cylindrical boiler has been patented in which a series of tubes for the escape of the products of combustion are shown extending in the sides to the top of the cylindrical body of the boiler, also that a boiler 125 has been patented with a narrow sectional

hood extending across the top and part way down one side and that stationary tube-reducers have also been patented, and I do not claim any of these; but,

5 Having fully described my improvements, what I claim is—

1. A boiler composed of two dome-shaped plates of metal united at their lower edges, and having a series of tubes arranged in one 10 or more horizontal rows near its lower edge as herein shown and described.

2. In combination with the dome-shaped boiler provided with a series of tubes arranged in one or more horizontal rows near 15 its lower edge, the dome-shaped hood com-

posed of two sheets or plates of metal united so as to be water-tight and provided with suitable inlets and outlets, said hood being of such shape and size as to completely envelop the boiler and leave a space all around 20 between it and the boiler for the passage of the products of combustion, substantially as and for the purpose set forth.

In testimony whereof I have signed my name to this specification in the presence of 25 two subscribing witnesses.

ISAAC D. SMEAD.
